INFANT'S OUTER GARMET

Joseph Astrove, New York, N. Y., assignor to Tidy
Products Corporation, New York, N. Y.

Application July 11, 1939, Serial No. 283,728

3 Claims. (Cl. 2—80)

This invention relates generally to infants' garments, and more particularly it relates to outdoor suits of the union type for infants such as are popularly called "Baby Bunting," or still more particularly to infants' outer garments.

Garments of this type as heretofore constructed have been open to the objection that they could not be conveniently applied to the infant because the garments could not be sufficiently opened up, and it was necessary to struggle with the wriggling and squirming infant in order to properly place his body and limbs within the garment as a pullover garment is difficult to apply to young infants.

It is therefore among the objects of my invention to provide in an infant's garment of the character described, a construction permitting the garment to be opened up to such an extent that the infant can be laid on it and thereafter his limbs inserted in the portions intended therefor, and the garment then closed up.

It is further among the objects of my invention to provide in an infant's garment a construction in which the garment is traversed by a plurality of slits running into a common opening and dividing the portions adjacent said opening into flaps which may be turned back so as to open up substantially the entire garment, and in which each slit is adapted to be closed or opened by a slide fastener.

It is also among the objects of my invention to provide a closure whereby the edges of two adjacent portions of a garment may be united in the form of a slide fastener and means for shielding said slide fastener against accidental opening.

It is the general object of my invention to provide, in an infant's garment, a construction that renders the garment simple, effective and economical, and assures great convenience in manipulation when applying or removing the garment, or for dressing such as in diapering the infant.

To attain these objects and such further objects as may appear herein or be hereinafter pointed out, I make reference to the accompanying drawing, forming a part hereof, in which:

Figure 1 is a view showing my improved garment laid out flat and completely closed;

Figure 2 is a view similar to Figure 1, but showing the garment completely opened up;

Figure 3 is a view of the upper portions of the garment showing a partial opening thereof;

Figure 4 is a sectional view substantially on the

line 4—4 of Figure 1, looking in the direction of the arrows;

Figure 5 is a modification of a detail of the construction.

5 In the drawing I have shown an infant's garment of the type mentioned comprising a body portion A, a head portion B, arm portions C and leg portions D.

The body portion A is shown as provided with 10 a slit 10 adapted to be closed in any suitable or preferred manner as by means of the slide fastener 11. The slit 10 has been shown as straight and centrally positioned in the front of the body portion A. As will be understood as the description

15 of the invention proceeds, it need not be so contoured and positioned, but other contours and positions such as a lateral position, a biased position, or a curved contour fastening may be preferable for certain purposes.

20 A head portion B is shown as in the form of a hood (although obviously it may be of other types) adapted to cover the back and the sides of the head of a wearer and provided with an opening 14 at the front, whereby the face of the 25 infant remains exposed.

Running along each arm portion C is a slit 12 which may commence at the distal end of the arm portion and run toward the opening 14 and into adjacency to the end of the slit 10, whereby 30 a flap 13 is formed, which, in the illustrative embodiment, may be described as being of triangular conformation.

It will be observed that because of the fact that the slits 10 and 12 run into this opening 35 14, so that when the flaps 13 are turned aside, as shown in Figure 2, the garment may be opened up at the front from the top of the head to the crotch.

The slits 12 may be closed by suitable means 40 provided for that purpose, such as the slide fasteners 15.

For additional security other fasteners may be provided, the function of which is to prevent the accidental opening of the slide fasteners.

45 For this purpose, I may, as shown particularly in Figure 4, mount the two sections 11a and 11b of the slide fastener on the edge portions 10a and 10b that define the slit 10, that said edge portions overlap each other and the fastener 11

50 is completely covered by said edge portions when they are in overlapping relation. For manipulation of the slide fastener the edge portion 10b is folded back. In order to prevent such folding back, and in particular to prevent the folding back at the end of the slit at which the slide or

pull 11c of the fastener 11 is positioned when the slit is closed, I have shown means for securing the edge portions 10a and 10b together. Such means, by way of example, has been shown as a snap fastener 16. Obviously other types of fasteners, such as button and button hole, would serve equally well for this purpose.

The slide fasteners 15 may, for the same purpose, have fastening means 17 positioned at their inner ends.

While the slits 12 have been shown as running into a common opening, namely the opening 14, and this is found in practice to be a convenient arrangement as it enables the use of a single snap fastener for each slit, it is to be understood that for certain purposes these slits may be otherwise disposed and may run into the slit 10 at some intermediate point. This however would of necessity involve modification of the fastening means.

It will also be apparent that the construction described is equally efficacious where no hood or head portion B is provided on the garment. In that case the various slits would run into the neck portion, separating the front portion of the garment into flaps.

A belt 18 provided with fastening means 19 intended for ornamental as well as utilitarian purposes, as will be understood, is also shown.

It will be clear from the foregoing description that my improved garment is readily positioned on an infant by laying the garment out back side down, opening all the fasteners and opening the flaps, laying the infant on his back, on the back side of the garment, inserting his legs in the leg pockets D, his arms in the arm portions C, and his head in the head portion B, and then closing all the fasteners. The resulting convenience, that avoids struggling with the infant when it is attempted to push his body into the garment through the ordinary restricted opening, which lacks the conveniently disposed flaps 13, while at the same time forcing his legs into the leg pockets and his arms into the sleeves, will be readily apparent to persons accustomed to handling infants.

The arm portion C may conveniently have their slits 12 commence at some distance from their extreme end portions, so that small pockets 20 are formed within which the infant's hands will be held sufficiently to prevent the ready withdrawal of his hands.

A modified arrangement of arm portion is shown in Figure 5, in which the arm portion C' is shown as provided with a cuff 21 adapted to surround the infant's wrist. The slit 12' then starts inside the cuff and is provided with fastening means such as the slide fastener 14'. In this construction, the infant's arm may readily be pushed through the cuff 21 by the accessibility afforded by the slit controlled by the slide fastener elements 14'.

It will therefore be evident that I have provided a simple and highly effective garment that affords great convenience in manipulation. In 65

particular the arrangement of slits radiating from a center so as to provide flaps enabling the garment to be opened up, permits the use of a single slide fastener for each slit, whereby the amount of manipulations required is greatly reduced.

It will be understood, of course, that I do not intend that the various features of my invention be necessarily used conjointly in the combinations herein disclosed, but that they are capable of use in other relations and in combinations different from the ones shown.

While I have herein disclosed one illustrative embodiment of my invention and a modification thereof, it will be understood that it may be embodied in many other forms and modified in many other ways without departing from the spirit thereof, as will be obvious to those skilled in the art, and that the disclosure herein is by way of illustration merely and is not to be interpreted in a limiting sense, and that I do not limit myself other than as called for by the language of the appended claims.

Having thus described my invention and illustrated its use, what I claim as new and desire to secure by Letters Patent is:

1. An infant's garment comprising a head section in the form of a hood open at the front, a body section, and a plurality of pairs of limb and arm sections the distal ends of which are closed to provide a partial enveloping connection, said head, body and a pair of limb sections being adapted to open up by an arrangement comprising a slit running down the front of the body portion, a slit running down each one of the said arm sections, and all of said slits merging into the opening at the front of the head section, and fastening means for separably uniting the edges of said slits.

2. An infant's garment comprising a portion for covering the back of an infant's body and his head, closed end pockets for receiving the legs of the infant, a pair of flaps forming the front of the body portion and a part of a pair of laterally extending arm portions having closed ends to provide a partial enveloping connection, separable closure means adapted to unite said flaps, a second pair of flaps forming another part of the said lateral arm portions and also the sides of the head portions, and separable closure means adapted to unite one flap of said last-named pair with the adjacent flap of the other pair.

3. In an infant's garment, a head section in the form of a hood open at the front, a body section, leg sections and arms sections closed at their ends, said body section being divided along a line running from the crotch to the neck, and said arm sections being divided along a line running along the front thereof and meeting the line of division of said body section, and said respective lines running into the opening in the head section.

JOSEPH ASTROVE.
